MIXING APPARATUS

George H. Haines, Caledonia, Ohio, assignor to
The Fairfield Engineering Company, Marion,
Ohio, a corporation of Ohio

Application October 21, 1936, Serial No. 106,795

9 Claims. (Cl. 259—3)

This invention relates to an apparatus and method for mixing and, in particular, for the mixing of feed, fertilizer, and the like.

While various mixers have been available heretofore, none of them, so far as I am aware, has been completely successful from the standpoint of the user. Batch-type mixers are objectionable because of the intermittent delivery characteristic. Continuous mixers are relatively 10 expensive and somewhat difficult to operate.

I have invented a novel mixing method and apparatus combining the simplicity of the batch-type mixers and the steady discharge characteristic of the continuous mixer. In accordance 15 with the invention, I provide a mixer comprising a revoluble shell or drum divided into a number of sections or compartments. In one of these, the material to be mixed is screened. It is then discharged into a batching compartment where 20 the various components of the desired mixture are collected. They are then discharged after some mixing, to the mixing section proper where thorough intermingling is effected. The mixed batch is then discharged to the packaging section 25 from which it is delivered into containers. Each section is refilled as soon as it is emptied, and a semi-continuous operation results.

For a more complete understanding of the invention, and the additional features of novelty 30 thereof, reference is made to the accompanying drawings representing a preferred embodiment, and the following detailed description. In the drawings,

Fig. 1 is a side elevation of the apparatus with 35 its foundation in section;

Fig. 2 is an end elevation looking from the right of Fig. 1;

Fig. 3 is an end elevation looking from the left of Fig. 1;

Fig. 4 is a longitudinal vertical sectional view 40 through the shell or drum, the supporting frame therefor being omitted;

Figs. 5, 6 and 7 are sectional views along correspondingly numbered lines V—V, VI—VI and 45 VII—VII of Fig. 4;

Fig. 8 is a plan view of one section of the screen mounted in the screening section of the mixer;

Fig. 9 is a sectional view through the screening section shown in Fig. 8, taken along the line 50 IX—IX;

Fig. 10 is a partial sectional view along the line X—X of Fig. 4; and

Fig. 11 is a sectional view of a detail taken along the line XI—XI of Fig. 4.

55 Referring now in detail to the drawings, the

mixer comprises a shell or drum 10 revolvably mounted on rollers 11, the drum 10 being provided with rims 12 resting on the rollers. The rollers are carried on shafts 13 journaled in suitable bearings mounted in a frame 14. One of the shafts 13 (that shown on the right in Fig. 2) is actuated by a gear drive 15 which, in turn, is driven by a chain belt 16. A pulley 17, or a direct-connected motor if desired, drives the chain belt 16.

As best shown in Fig. 4, the shell 10 is divided into a screening section 18, a batching section 19, a mixing section 20, and a packaging section 21 (which for convenience will hereafter be referred to as a bagging section) by transverse partitions 22 secured to and rotating with the shell. The left-hand end of the drum, as viewed in Fig. 4, is closed by a wall 23 similar in all respects to the partitions 22. The right-hand end of the drum has an inturned flange 24.

A return conveyor 25 extends inwardly of the right-hand end of the shell and carries a cover plate 26 which closes the open end thereof. The conveyor 25 comprises a trough 27 which is preferably lined with sheet rubber vulcanized thereto, a screw 28 carried on a shaft 29, and a cover 30. The outer end of the conveyor trough is supported on the frame 14. The inner end is supported by a stationary bearing 31 in which the shaft 29 rotates, and is anchored to a secondary partition 32 secured to and rotating with the shell. The plate 26 is provided with a hopper 33 through which material may be introduced into the interior of the screening section 18.

Material to be mixed is delivered to the hopper 35 from a chute 34 extending downwardly from an elevator 35. The elevator extends upwardly from a pit 36 in the foundation on which the frame 14 rests, and receives material from a hopper 37 into which it may be dumped from 40 the floor level, by means of a feeder 38. The feeder 38 is driven from the sprocket on the foot shaft of the elevator 35 by a gear and chain drive 39. The elevator 35 is driven by a belt 40 from the driven shaft 13.

A screen 41 is mounted within the screening section 18 of the drum, and is composed of a plurality of sections 42, such as shown in Figs. 8 and 9. Each of these sections comprises a frame 43 having a mesh panel 44 secured therein. The 50 inner surface of each section 42 is provided with a plurality of vanes 45 disposed at an oblique angle as shown in Fig. 8, so as to advance material within the screen 41 from right to left therethrough. Conveyor flights or inter-elevators 46 55

are secured to the vanes 45 and serve to pick up excess material collecting in the bottom of the screen and discharge it downwardly across the screen sections after raising it to the top thereof.

5 As shown in Fig. 5, the screen sections are disposed inwardly above the shell, leaving a space therebetween for the material which passes through the screen. Vanes 47, similar to those shown at 45, are mounted in this space to move 10 axially of the shell the material which has passed through the screen. Plungers 48 are slidably mounted in tubular guides extending radially into the shell. The plungers are adapted to engage the abutting edges of adjacent screen sections. Trip hammers 49 are pivoted to the frame 14. Blocks 50 having inclined faces are disposed peripherally of the shell to engage and raise the hammers 49. As the blocks pass thereunder, the latter fall through a short distance and strike 15 plungers 48. This vibrates the screen sections and causes the dislodgment of any material adhering thereto.

The cover 30 of the conveyor 25 terminates short of the inner end of the trough 27. Radial 25 vanes 51 deliver to the trough 27 any lumps which have not been broken up after moving the length of the screening section. The shaft 29 of the conveyor, being secured to the partition 32, rotates therewith, and moves the lumps 30 delivered to the trough in the direction indicated by the arrow. A pulverizer (see Figs. 4 and 11) is mounted at the outer end of the trough 27 and comprises a set of radial breaker arms 52 mounted directly on the same shaft as 35 the pulley 17, and a chute 53 discharging into the lower portion of the elevator 35. The breaker arms 52, being driven at relatively high speed, serve to break up the lumps discharged from the outer end of the trough 27, and the 40 pulverized material is then re-delivered to the screening section by the elevator.

Radial vanes 54 similar to those shown at 51 collect the material which passes through the screen, and is moved axially of the drum by the 45 vanes 47 and discharge it through a central opening in the partition 22 to the batching section 19. Parallel plates 55 extend into the mixer from the lefthand end and have inclined plates 56 disposed therebetween to form chutes for conveying material from one section to the next. The outer ends of the plates 55 are supported 50 on the frame 14, while the inner ends are supported on a bearing 57 on the inner end of the shaft 29. The chutes 56 between the sections 19 and 20 and 20 and 21, as well as a similar chute 58 which discharges material from the section 21 to a discharge spout 59, are provided with covers 60 which may be manually operated from the left-hand end of the drum by 60 rods 61. So long as it is desired to retain a given batch of material in a particular section, the cover 60 for the chute 56 leading to the next section is kept closed. The material in the particular chamber is then subjected to continued 65 agitation. When the cover 60 is withdrawn, vanes 62 dump the material onto the associated chute 56 which conveys it to the next section.

No cover is needed for the chute 56 leading from the screening section 18 to the batching 70 section 19, because it is desirable that the material to be mixed be delivered to the batching section as soon as it has passed through the screening section. The batching section 19 is provided with vanes 63 which cause the material to move 75 from right to left therethrough. These vanes

also produce some mixing, but the mixing section 20 is relied on principally for this purpose. It has radial mixing vanes 64 which are highly effective for this purpose, in addition to the conveying vanes 63. The bagging section 21 is 5 similar to the batching section 19.

At the discharge end of the mixer, bag holders 65 are supported below the discharge spouts 59 from scale beams 66. The holders have individual gates, and a gate 67 in the hoper 58 permits either of the spouts 59 to be selected. Bags are attached to the holder 65, as indicated at 68, and are filled to a predetermined weight.

Each of the sections 19, 20 and 21 has a pair of windows 69 and 70 disposed therein, as shown in 15 Figs. 1, 6 and 7. Light sources 71 are disposed in the paths of the windows so that light rays from the sources 71 which would pass through the windows, when the latter are in line therewith, if the sections were empty, will be obscured 20 by material in each section until it is discharged into the next section. When all the material in a given section has been discharged to the next section, the light path through the former will be unobstructed. Mirrors 72 properly disposed 25 will reflect the transmitted light to the operator at the left-hand end of the mixer indicating the empty condition of that section. The operator will then proceed to operate his gate controls to refill the section. 30

As has probably already been sufficiently indicated, the material to be mixed is dumped into the hopper 37 and delivered to the screening section 18 by the elevator 35 through chute 34. The fines passing through the screen are delivered to 35 the batching section 19 by the vanes 54 and the cooperating chute 56. Lumps are delivered to the return conveyor 25 by the vanes 51. The lumps are then pulverized by the breaker arm 52, and the pulverized material returned to the 40 elevator.

When all the components of a batch have been collected in the chamber 19, the operator shifts the cover 60 cooperating with the chute 56 leading from the section 19 to the section 20, and the 45 batch is then discharged into the latter section. The cover 60 is then replaced and another batch is collected in the section. The mixing of the first batch proceeds in the section 20 and, when thoroughly mixed, the cover 60 over the chute 50 leading to the bagging section 21 is moved, and the material discharged into the latter. The second batch is then transferred to the mixing section, and the collection of a third batch in section 19 is started. The first batch, after being mixed 55 in the section 20, is delivered into containers from the section 21.

The apparatus thus performs a semi-continuous batching method. While each batch of material is mixed individually, the progression of the 60 batches is such that the components of the mix may be fed in almost continuously, and the resulting mixture may be packaged in the same way.

It will be apparent from the foregoing description that the apparatus and method of my invention are characterized by numerous advantages. The apparatus is relatively simple in construction and easy to operate so that it may be operated by relatively unskilled labor. The device is highly effective and insures a thorough screening of 70 all material, as well as a perfect intermingling of the components of the mixture. Since the method performed is semi-continuous, efficient operation and a large production are obtained. The performance of the several steps in different sec- 75

tions insures the segregation of the batch being mixed from the batch previously mixed, but not discharged, as well as from the materials being collected prior to mixing. The return conveyor 5 for the lumps, together with the pulverizer, further contributes to thorough mixing, since without these features, the lumps would be carried over into the mix, in the form of masses of entirely unmixed material. The rubber lining of 10 the return conveyor greatly increases its life and avoids accumulation of material which might adhere to a wood or steel surface.

Although I have illustrated and described herein but one preferred form of invention, it will be 15 understood that changes in the construction disclosed may be made without departing from the spirit of the invention or the scope of the appended claims.

I claim:

20 1. In a mixer, a revolving drum, partitions dividing it into a plurality of sections including a screening section at one end, a lump conveyor extending into the screening section, a chute frame extending into the drum from the other end, said 25 conveyor and frame having inner bearings supported on the partition between the screening section and the adjacent section.

2. The apparatus defined by claim 1 characterized by said conveyor including a revoluble 30 member secured to and rotating with said drum.

3. In a mixer comprising a rotary shell or drum divided into compartments, a screen extending around the inside of the first or receiving compartment, means for delivering the material to be 35 mixed to the space within said screen, means for moving materials passing said screen to a second or batching compartment, means including chutes having manually operable gates for moving material from the batching compartment to a third 40 or mixing compartment, and thence to a fourth or packaging compartment, and a discharge spout extending from the packaging compartment for filling containers with mixed material.

4. In a mixer, a revolving drum, partitions dividing it into a plurality of sections including a screening section at one end, a lump conveyor extending into the screening section, and a chute frame extending into the drum from the other end, having chutes thereon for discharging material from each section to the next.

5. A mixer comprising a shell mounted for rotation, partitions dividing the shell into sections,

means in said sections for moving material axially thereof, openings in said partitions, chutes for discharging material from one section to another, means for supporting said chutes in fixed position including a pair of plates extending through said sections, and manually operable gates for closing said chutes. 5

6. A mixer comprising a shell mounted for rotation, partitions dividing the shell into sections, means in said sections for moving material axially 10 thereof, stationary chute supporting members extending axially into said shell from one end thereof, the inner ends of said members being supported on a bearing carried on the rotating shell and chutes for feeding material from one section to the next, manually operable gates for closing said chutes, and means in each section for delivering to one of said chutes the material which has 15 collected in that section.

7. In a rotary mixer, the combination with a 20 batching section for receiving measured amounts of the components of a mixture, a mixing section for mixing a batch of material while another is being collected in the batching section, and a packaging section for receiving a mixed batch 25 from the mixing section, of fixed supports extending into the mixer from one end thereof, chutes carried on said supports for discharging material from one section to another, a cover for each chute and operating means for said covers extending along said supports to the exterior of the shell. 30

8. A mixer comprising a shell mounted for rotation, partitions dividing the shell into sections, means in said sections for moving material axially 35 thereof, openings in said partitions, chutes extending through said openings for discharging material from one section to another, means extending axially into the shell from one end thereof for supporting said chutes in a fixed position, and manually operable gates for closing said 40 chutes.

9. A mixer comprising a shell mounted for rotation, partitions dividing the shell into sections, means in said sections for moving material axially 45 thereof, openings in said partitions, chutes for discharging material from one section to another, means extending through said sections for supporting said chutes in fixed position, a bearing in the shell supporting said means interiorly of the shell, and manually operable gates for closing 50 said chutes.

GEORGE H. HAINES.
